US0D1042376S

(12) **United States Design Patent** (10) Patent No.: **US D1,042,376 S**
Saito et al. (45) Date of Patent: ** Sep. 17, 2024

(54) **SEMICONDUCTOR MODULE**

(71) Applicant: **ROHM CO., LTD.**, Kyoto (JP)

(72) Inventors: **Koshun Saito**, Kyoto (JP); **Koki Nakano**, Kyoto (JP)

(73) Assignee: **ROHM CO., LTD.**, Kyoto (JP)

(**) Term: **15 Years**

(21) Appl. No.: **35/518,119**

(22) Filed: **Aug. 24, 2022**

(80) **Hague Agreement Data**

Int. Filing Date: **Aug. 24, 2022**

Int. Reg. No.: **DM/223153**

Int. Reg. Date: **Aug. 24, 2022**

Int. Reg. Pub. Date: **Aug. 25, 2023**

(30) **Foreign Application Priority Data**

Feb. 25, 2022 (JP) ..... 2022-003659 D

(51) **LOC (14) Cl.** **13-03**

(52) **U.S. Cl.**

USPC **D13/182**

(57)

CLAIM

The ornamental design for a semiconductor module, as shown and described.

DESCRIPTION

1. Semiconductor module

1.1 : Perspective

1.2 : Perspective

1.3 : Front

1.4 : Top

1.5 : Bottom

1.6 : Right

1.7 : Left

The broken lines in the drawings form no part of the claimed design; the dash-dotted lines in the drawings represent the

(Continued)

unclaimed boundaries and form no part of the claimed design; the back view is omitted since it is symmetrical to the front view.

1 Claim, 7 Drawing Sheets
